DESIGN FOR A LIGHTING FIXTURE

Otto G. Hildebrand, Cleveland, Ohio

Application July 24, 1936, Serial No. 64,029

Term of patent 7 years

To all whom it may concern:

Be it known that I, Otto G. Hildebrand, a citizen of the United States, residing at Cleveland, in the county of Cuyahoga and State of Ohio, have invented a new, original, and ornamental Design for a Lighting Fixture, of which the following is a specification, reference being had to the accompanying drawing, forming part thereof, wherein Fig. 1 is a view in side elevation; Fig. 2 is a bottom plan view; and Fig. 3 is a sectional elevation on the line 3—3 of Fig. 1, of a lighting fixture showing my new design.

The dominant feature of my design resides in the portions thereof shown in solid lines.

I claim:

The ornamental design for a lighting fixture, substantially as shown and described.

OTTO G. HILDEBRAND.
